(57) **CLAIM**

I claim the ornamental design for a holiday-themed light cover set, as shown and described.

DESCRIPTION

FIG. 1 is a perspective view of a holiday-themed light cover set, showing my new design;

FIG. 2 is a front elevational view of a first holiday-themed light cover of the invention, the rear elevational view being a mirror image thereof;

FIG. 3 is a left-side elevational view of the first holiday-themed light cover of the invention,

FIG. 4 is a right-side elevational view thereof;

FIG. 5 is a top plan view thereof;

FIG. 6 is a bottom plan view thereof;

FIG. 7 is a front elevational view of a second holiday-themed light cover of the invention, the rear elevational view being a mirror image thereof;

FIG. 8 is a left-side elevational view thereof, the right-side elevational view being a mirror image thereof;

FIG. 9 is a top plan view thereof;

FIG. 10 is a bottom plan view thereof;

FIG. 11 is a front elevational view of a third holiday-themed light cover of the invention, the rear elevational view being a mirror image thereof;

FIG. 12 is a left-side elevational view thereof, the right-side elevational view being a mirror image thereof;

FIG. 13 is a top plan view thereof; and,

FIG. 14 is a bottom plan view thereof.

The broken lines showing a light string in FIG. 1 are included for the purpose of illustrating the invention in use, and form no part of the claimed design.

The holiday-themed light covers are shown separately in FIGS. 2–14 for clarity of illustration.
